UNITED STATES PATENT OFFICE.

WILLIAM HERBERT BORDEN, OF WINCHESTER, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

FASTENING-INSERTING MACHINE.

1,276,019.

Specification of Letters Patent. Patented Aug. 20, 1918.

Application filed December 16, 1914. Serial No. 877,596.

To all whom it may concern:

Be it known that I, WILLIAM HERBERT BORDEN, a citizen of the United States, residing at Winchester, in the county of Middlesex and State of Massachusetts, have invented certain Improvements in Fastening-Inserting Machines, of which the following description, in connection with the accompanying drawings, is a specification, like reference characters on the drawings indicating like parts in the several figures.

The present invention relates to fastening inserting machines and particularly to machines adapted to insert metallic reinforces or protectors in the soles or heels of boots and shoes.

An object of this invention is to provide a machine for presenting and inserting protectors of the type known to the trade as "tadpole" protectors. These protectors have each a head portion comprising laterally extending wings shaped to embrace the stock into which the protector is driven and a shank depending from the head between the wings, a protector of this type being shown in United States Letters Patent No. 889,383 to S. D. Leland, dated June 2, 1908.

An important feature of the invention is improved means for holding the protector in proper position under the driver and for maintaining it in proper position while it is being driven. As illustrated this means is constructed and arranged to prevent axial turning of the protector while it is being driven and thereby insure that it be inserted in the stock with its wings properly disposed.

Another feature of the invention is a novel awl constructed and arranged to form an opening adapted to receive a protector of the type above described.

These and other features of the invention will be understood from the following specification which describes in connection with the drawings one embodiment of my invention.

Figure 1 is right hand side elevation of the upper part of a machine embodying my invention;

Fig. 2 is a detail showing the toothed rod

or shaft for adjusting the edge gage and the actuating means therefor;

Fig. 3 is a front end elevation of the upper part of the machine shown in Fig. 1, with the movable body of the hopper detached; 55

Fig. 4 is an enlarged plan view of the raceway detached from the machine; the raceway cover being removed;

Fig. 5 a section on the line 5, 5, Fig. 3; 60

Fig. 6 a section on the line 6, 6, Fig. 3;

Fig. 7 is an enlarged detail, in front elevation, of the delivery end of the raceway and of the throat containing the driver passage and the protector guide;

Fig. 7^a is a detail showing the presser and part of the raceway cover; 65

Fig. 8 is a left hand side view of the parts shown in Fig. 7, with the raceway omitted, the protector guide being shown by dotted lines; 70

Fig. 9 is a plan view of the parts shown in Fig. 7;

Fig. 10 is a view similar to Fig. 9, with some of the parts in section, the protector delivering device being represented by dotted lines in its operative position; 75

Fig. 11 is a view of the parts shown in Fig. 8, with the cover plate of the driver passage detached and turned over, the device for removing the protectors being omitted. 80 This figure shows a protector resting upon its support ready to be driven;

Fig. 12 is a section on the line 12, 12, Fig. 11 with the cover plate of the driver passage in place; 85

Fig. 13 shows a side elevation and an end view of the driver;

Fig. 14 shows a side elevation and lower end view of the awl;

Fig. 15 illustrates the hole or slit made by the awl in the top lift, this view also showing driven protectors; 90

Fig. 16 shows in side and front elevation and in plan one of the novel protectors which the machine to be herein described is particularly adapted to handle. 95

The invention may be embodied in nailing machines of various types, but is herein shown, for convenience, as applied to a nailing machine of the type shown and described 100

in United States Patent No. 490,624 dated Jan. 24, 1893.

In the drawings the column 2, head 3 in which the main shaft 5 has its bearings, the 5 swinging frame 6, the foot plate 7, the driver bar 8, the awl bar 12, the rotatable hopper 13, the separator lever 15, the means for actuating the driver bar and the awl bar, the means for imparting lateral movement to 10 the frame 6 that the awl may feed the stock, and means for rotating the hopper and for actuating the lever 15, may be substantially as shown and fully described in said Patent No. 490,624.

15 The work support or horn 16, partially shown, is in practice normally pressed upwardly by a suitable spring to clamp the work between the horn and the foot plate and is depressed between successive inserting operations to release the work sufficiently so that it may be fed. The horn may be further depressed by a treadle at the completion of the operation of the machine to allow the work to be removed from the 20 horn and other work applied thereto, the work support controlling mechanism being substantially that shown in United States Patent No. 265,227, dated Sept. 26, 1882.

To enable protectors having depending 30 shanks to be controlled and driven by the machine referred to, a novel raceway is provided. This raceway comprises front and rear walls or plates 17, 18, with an assorting device 19 shown as a plate rising 35 above the rear wall 18 of said raceway, the assorting device being held in place by suitable screws 20 extending through the front wall 17 of the raceway, said screws also passing through a standard 24 which sus- 40 tains the shelf 21.

The assorting device 19 is located opposite the lower end of the shelf 21 and projects above the same, the face of said device forming a continuation of the face of 45 the rear wall 18 of the raceway. The upper end of the front wall 17 is separated quite a distance from the rear wall 18 by spacing blocks 22, so that the shank of a protector can freely enter the passageway 50 between said walls, with the underside of the laterally extending wings of its head resting upon the edge of the front wall 17, the passageway being not wide enough to permit the head of the protector to pass 55 therethrough. The upper end of the front wall 17 is beveled on opposite sides from a sharp to a gradual bevel, as shown in Figs. 4, 5 and 6, so that it is impossible for a protector to hang upon said front wall unless 60 the shank of the protector projects into the passageway between the front and rear walls, consequently only those protectors will be positioned properly which drop from the shelf 21 with their shanks projecting

downwardly and with the laterally extending wings of their heads projecting away from the assorting device 19. All of the other protectors, namely, those which drop from the shelf head first or with their laterally extending wings projecting toward the 70 assorting device, will engage the beveled portion of the front wall and be deflected into the hopper. The rear wall 18 of the raceway is slightly higher than the front wall 17 and is adapted to be engaged by 75 the outer side of the head of the protector, so as to prevent the protector from turning as it travels down the raceway with its shank projecting into the passageway and with the underside of its laterally extending 80 wings resting upon the edge of the front wall. The front and rear walls of the raceway are held together by screws 23, spacing blocks being interposed between the walls to determine the width of the pas- 85 sageway. At the extreme upper end of the raceway, resting upon the front wall 17 is a block 25 which is fastened to the assorting device by screws 26, as shown in Fig. 3.

The raceway near its upper or receiving 90 end is provided, see Fig. 4, with a contracting device, herein shown as a plate 27 adjustably secured by suitable screws 28 to the rear wall 18 of the raceway, said device being made adjustable to enable the width 95 of the raceway groove which receives the shanks of the protectors, to be varied. By adjusting the plate 27, the width of the raceway groove at the entrance thereto may be made to correspond to the thickness of 100 the shank of the protector, so that only those protectors will pass through the entrance to the raceway which present the edges of their shanks to the groove of the raceway, thus causing the protectors to oc- 105 cupy a position on the raceway with the under sides of their heads resting on the top of the wall 17 and with the wings of the protectors extending in the same direction.

Bearing upon the raceway near the contracting device is a kick-off, shown in Figs. 3 and 6 as a lever 29 pivoted on a screw 30 in the stationary part 32 of the hopper, a suitable spring 33 acting to keep the longer 110 end of the kick-off normally pressed against 115 the upper side of the rear wall 18 of the raceway.

The raceway is connected to and reciprocated with the swinging frame 6 as the latter is moved to effect the feeding of the 120 stock, as provided for by the disclosure in said Patent No. 265,227. As the raceway is reciprocated any protectors having their shanks but partially in the raceway groove, or any protectors which are lodged im- 125 properly on the raceway, are struck by the kick-off and dislodged from the raceway.

The raceway cover 35, of usual charac-

ter, has extended beyond its lower end a yielding presser 36, see Figs. 7 and 7^a, which bears on the top of the head of the protector immediately back of the endmost protector 5 next to be fed from the raceway into the driver passage to be described.

The throat of the machine, as shown, comprises several members 39, 40, 41, connected with each other and with the frame 6 by 10 suitable bolts 42 entering holes therein. The member 39 has a driver passage 43, Fig. 8 and an awl passage 45, and the member 41 forming one side of the driver passage is shown as connected with the members 39 15 and 40 by suitable screws 46 and 48, the screw 48 also serving as a pivot for the protector guide 49 which is yieldingly sustained in the driver passage by a spring 50. The plate 41 is provided with a slot or 20 throat 52 which forms a continuation of the groove in the raceway, and the shanks of the protectors fed from the raceway travel through said throat into the driver passage. The members 39, 40, of the throat are held 25 together by a suitable screw 53, and by a tongue on the member 40 which enters a groove in the member 39, see Fig. 9.

The protectors are delivered singly from the raceway, by a delivering device consisting of a slotted lever 55 fulcrumed at 56, and having an acting end 58 which is so shaped and located with relation to the raceway and the driver passage that when the lever 55 is moved from its inoperative full-line position, Fig. 10, into its operative dotted line position, it will engage the head of the endmost protector, and push said protector longitudinally from the end of the raceway into the driver passage. The back 40 of the acting end 58 of the lever serves to retain the other protectors in the raceway, and without moving said protectors backwardly or up the raceway, prevents them from moving down the raceway until after 45 the delivering device has been restored to its inoperative or full-line position.

The protector delivering device derives its movement from a roller or stud 59 carried on the lower end of the lever 15, said lever 50 being moved in one direction by a cam mounted on the main shaft and in the other direction by a spring 60, as shown in Fig. 3. As soon as the delivering device arrives in 55 its retracted position the blow of the descending driver jars the raceway so that the protector then held by the yielding presser 36 will be released and will slide down the raceway toward the delivery end thereof, the pressure of the protectors behind the 60 one so acted upon by the presser being sufficient to cause the endmost protector to slide out from under the presser.

The protector delivering device in its movement from its full-line position into its

dotted line position, Fig. 10, pushes a protector in front of it, from the delivery end of the raceway, the shank *b* of the protector passing through the slot 52 in the member 41, and deposits the protector in the driver passage with the underside of the head of 65 the protector resting upon a support 61, pivoted at 62 and occupying a position in the driver passage. A spring 63 acts to maintain the support normally in a substantially horizontal position, said support yielding to 70 enable the protector to descend as the latter is acted upon by the driver 9, the lower end of which is grooved or recessed, see Figs. 11 75 and 13, to straddle a protector guide 49.

When the driver descends and meets the 80 protector, the support 61 yields, and the inner side of the shank of the descending protector is acted upon by the outer end of the guide 49 which enters the open space between the laterally extending wings of the 85 protector, the acting end of the guide remaining in contact with the inner side of the shank of the protector and with the inner side of the head thereof throughout the driving operation, thus keeping the protector 90 in an upright position, and preventing it from turning axially in the driver passage, so that the protectors will all be driven uniformly with the wings of their heads in alined position. 95

To drive a protector of this shape into the work sustained upon the work support, it is preferable first to make a hole in the stock to receive both the shank and the head of the protector. This is accomplished in the 100 illustrated machine by means of an awl 65 having a round hole bored in its lower end, see Fig. 14, and beveled upwardly from its lower end more or less, according to the length of the protector and the shape of the head. 105 Such an awl will make a hole for the shank of the protector, and an arc-shaped cut, see Fig. 15, to receive the underside of the head of the protector where it branches from the shank thus insuring the proper starting of 110 the protector into the work.

In the operation of the machine the awl descends and penetrates the stock, and while the awl is in the stock the frame 6 is moved laterally to feed the stock over the work 115 support or horn, the horn being at this time slightly depressed. The stock having been fed, the awl rises and the work support clamps the stock against the foot plate and holds it clamped while the frame 6 is moved 120 backwardly to bring the protector driver into alinement with the hole in the stock made by the awl. During this operation a protector has been delivered from the raceway into driving position upon the yielding 125 shelf or support 61, and the protector driver then descends and engages said protector and drives it into the work, the protector

leaving the support and straddling the guide 49 which holds the protector in a vertical position in the throat and prevents it from turning axially while it is being driven 5 into the work.

5. The edge gage 70 has a connected toothed block 72, which is engaged by the teeth 73 of a long pinion having other teeth 75 on its opposite end and sustained in a frame 76 connected to the head 3, by a screw 77. 10 The frame contains two pinions 78 and 79, the pinion 78 engaging the teeth 75 of the long pinion and being moved by the pinion 79. The pinion 79 has a connected crank 80 through which is extended a locking pin or 15 device 82 which cooperates with a series of holes 83 formed in the block 76. Whenever it is desired to change the position of the acting end of the edge gage 70, the locking pin is withdrawn and the crank is turned 20 to move the gage into the desired position, the locking pin then entering a different hole to retain the gage in its adjusted position.

25 Having described my invention, I claim as new and desire to secure by Letters Patent of the United States:—

30 1. In a machine for driving protectors, a throat having a driver passage, a driver, means for supporting a protector in the driver passage, and a yielding device in 35 said driver passage for guiding the protector while it is being driven.

35 2. In a machine for driving winged protectors, a driver, a movable device for sustaining the protector, and a yielding guide adapted to enter the space between the wings of the protector and guide the protector while it is being driven.

40 3. In a machine for driving winged protectors, a throat having a driver passage, a driver, and a yielding guide located in the driver passage constructed and arranged to enter the open space between the wings of 45 the protector and press the protector yielding against one wall of the driver passage while it is being driven.

45 4. In a machine for driving winged protectors, a throat having a driver passage, a movable support in said driver passage to receive and sustain a protector, and a yielding guide located in the driver passage below the said support and constructed and arranged to enter the space between the 55 wings of the protector after it leaves the support.

50 5. In a machine for driving winged protectors having depending shanks, a throat having a driver passage, a guide located in the driver passage constructed and arranged to enter the space between the wings of the protector, and means to cause said guide to 60 act against the shank and the inner side of the head of a protector and press it against

the wall of the driver passage while the 65 protector is being driven.

6. In a machine for inserting fastenings, a throat having a driver passage, a driver, means for supporting a fastening in the driver passage, and a device projecting into 70 the driver passage below the said support constructed and arranged yieldingly to engage one side of the fastening along its length and maintain it against the wall of the driver passage while it is being driven. 75

7. In a machine for driving protectors having depending shanks, a raceway constructed and arranged to guide a protector into position to be inserted in the work and having a slot adapted to receive the shank of 80 a protector to prevent its rotation, a throat having a driver passage, means to feed the endmost protector from the raceway into the driver passage, and means for suspending the protector in the driver passage prior 85 to its insertion in the work.

8. In a machine for driving winged protectors having depending shanks, a raceway arranged to guide a protector into position to be inserted in the work, a throat 90 adjacent to the lower end of said raceway and provided with a driver passage, means to deliver the endmost protector from the raceway into said driver passage, a yielding guide located in said driver passage, 95 constructed and arranged to press the protector against the wall of the driver passage, a driver slotted at its lower end to embrace said guide, and means to actuate said driver. 100

9. In a machine for driving protectors having depending shanks, a slotted raceway, a throat having a driver passage, a member provided with an opening in line with the slot of the raceway, means to deliver a protector through said opening into the driver passage, a driver, actuating means therefor, a yielding support to sustain said protector preparatory to its being acted upon by the driver, and means to 110 guide the protector while it is being driven.

10. In a machine of the class described, a driver, means to actuate it, a throat having a driver passage, and a yielding guide projecting into said driver passage and acting 115 on the inner side of a protector to press its outer side in contact with the wall of the driver passage, said guide maintaining the protector in upright position and guiding the protector throughout its movement in 120 the driver passage.

11. In a machine for driving winged protectors having depending shanks, an awl adapted to make an incision in the stock of a shape corresponding approximately to 125 that of the shank and head of the protector to be driven, a throat having a driver passage, means for delivering protectors into

said driver passage, and a driver to drive protectors into the incisions made in the stock by the awl.

12. In a machine for inserting fastenings, 5 a throat having a driver passage, a device projecting into the driver passage constructed and arranged yieldingly to engage one side of a fastening along its length and press it against the wall of the driver passage while it is being driven, a driver arranged to straddle said device during its operative movement, and means to actuate said driver.

13. In a machine for driving winged protectors having depending shanks, an awl for cutting a hole in the stock to receive a portion of the protector, a throat having a driver passage, a protector guide located in said passage, means to deliver a protector 20 into said passage, a driver adapted to straddle said guide, and means to actuate said awl and driver.

14. In a machine for inserting fastenings, the combination with a fastening inserting mechanism, of an awl for making a fastening receiving incision in stock, the awl having a hollow stem and a cutting edge lying substantially in a plane oblique to the axis of the stem. 25

15. In a machine for inserting fastenings, 30 the combination with a fastening inserting mechanism, of an awl having a hollow cylindrical stem, and a cutting edge lying substantially in a plane oblique to the axis of the stem for making an arc shaped fastening receiving incision in stock. 35

In testimony whereof I have signed my name to this specification in the presence of two subscribing witnesses.

WILLIAM HERBERT BORDEN.
